COMBINATION KNEE AND ANKLE JOINT

Roderick W. McKendrick, Salt Lake City, Utah

Application April 8, 1948, Serial No. 19,823

13 Claims. (Cl. 3-2)

1

My invention relates to artificial limbs and has for its object to provide a new and highly efficient combination knee and ankle joint adapted to operate in the identical manner that the original limb operated the knee and ankle to take and assume the same movements and twists that the original limb took before amputation.

A further object is to provide a functional knee joint for above the knee artificial limbs which will eliminate many parts, and much expensive material and which will accomplish a better result than possible with the old style knee joint or with certain highly complex knee joints recently developed.

A still further object is to provide a self-aligning knee and ankle combination artificial limb which is so constructed that when used it will align itself to the different individual movements and oddities each individual has in their walking habits, and which will compensate for and assume the correct movements to make movements of the limbs natural for a person having knock knees, bow legs, or other like differences of body formation and with the knee adaptable for adjustment up or down one fourth inch totaling one half inch in adjustment for height which is a much greater distance for adjustment than has heretofore been possible with artificial limbs.

A still further object is to provide an artificial limb which gives free action on front and back motion, lateral motion and rotation in the knee thus providing freedom of movement never possible with any artificial limb.

A still further object is to provide a brake and lock in the knee joint controlled by the position of the toe and leg to meet the individual needs of each person needing such a limb.

In manufacturing such a limb the points of rotation can be varied as much as twenty-five per cent from extreme knock knee to extreme bow legged types in five minutes' time without changing the construction of the original installation which will cut down construction costs and labor at least four hours for each artificial limb, and often will save as high as one entire day usually spent in alignment and fitting.

These objects I accomplish with the device illustrated in the accompanying drawings in which similar numerals and letters of reference indicate like parts throughout the several views and as described in the specifications forming a part of this application and pointed out in the appended claims.

Figure 1 is a side view of an artificial limb of my design.

2

Figure 2 is a rear view thereof.

Figure 3 is an enlarged vertical section of the knee and ankle joint medial portions cut away.

Figure 4 is a transverse section of the knee joint.

Figure 5 is a transverse section of the ankle joint.

Figure 6 is a view of the ball and socket used in the ankle joint.

Figure 7 is an end view of Figure 6.

Figure 8 is a view of the ankle shaft removed from the ball.

Figure 9 is an exploded view of the ball and socket the ball being removed from the socket.

Figure 10 is a view of the socket support and bolt.

Figure 11 is an end view of the ball and socket used in the knee joint.

Figure 12 is a view of the shaft used in the knee joint.

Figure 13 is an exploded view of the ball and socket used in the knee joint.

Figure 14 is a view of the socket support bolt used in the knee joint.

Figure 15 is a plan view of the knee adjusting plate for vertical adjustment.

Figure 16 is a diagrammatical section of Figure 15.

In the drawings I have shown the artificial leg as the socket A into which the stump is fitted in the usual manner. The socket A is joined to the medial leg or knee to ankle section B of the leg by a special joint and the foot C is joined by a similar new ankle joint, the entire assembly providing a new artificial limb having many adjustments not possible with the usual artificial limbs, yet using substantially the same joints in the knee joint as in the ankle joint, the ball and socket portions being absolutely identical except in some instances they will be of different sizes, but in most cases these two joints will be identical.

Each joint consists of an eyebolt having a shaft threaded to receive a nut or to be screwed down into a socket depending upon its use as an ankle or a knee joint. This eyebolt carries a socket therein in which a ball is mounted the ball being provided with a hole through which a shaft is passed, the shaft being locked in the position required whether it be the knee or ankle. These features are essentially identical in both joints.

Describing the knee joint first I will illustrate the eyebolt as 5, carrying a socket 6 and ball 7, through which ball the shaft 8 is passed. The socket A is provided with a vertical cut D in the

back of the knee and the joint is mounted there-in with rubber bumpers or washers 9 and 10 mounted one on each side of the joint with the shaft 8 extending from outside to outside of the leg. This joint is set much farther back than is the usual manner and is braced by the forward-
ly extending leg portion 10 engaging the knee cap portion of the leg as shown in Figure 3, as well as by the body of the stump engaging the socket 11 into which the threaded eyebolt 5 is screwed. Each end of the shaft 8 is held in place by a set screw 12. The knee is attached to the leg portion B by securing the internally threaded socket or eyebolt receiver 13 first to the plate 14 of the leg by the bolts 14 being passed through the flange 16 and then by screwing the eyebolt down into the receiver 13 and when properly adjusted for height and throw the eyebolt is locked in position by a set screw 17. The eyebolt receiver 13 is formed centrally 15 on the round flange 16 and the flange is secured onto the plate 14 by four bolts 15.

Where it is not desired to use the brake and lock on the knee joint this finishes the joint with the exception that the lower end of the slot D in the socket A is formed with arcuate cuts 18 and 19, to permit a certain amount of lateral movement which movement will, of course, be compensated for and the shock in the rubber bumpers or washers 9 and 10.

Where it is desired to have the relative position of the toe or foot control a brake to lock the knee joint from buckling or other movement, the eyebolt is cut and provided with extended ears 20 and 21 with a bolt hole bored there-through to receive a bolt 22 carrying a brake lever 23. This lever 23 extends back and has a cable 24 attached to the end thereof, and when the cable 24 is drawn down the lever 23 will be moved, acting as a brake lever drawing the two ears 20 and 21 together constricting the bore of the eyebolt onto the socket 6, locking the knee joint from movement. The lower end of the cable 24 is attached to a ball 25 which is carried in an adjustable receiver 26 mounted in the foot C, with the receiver being held in place by the bolt end 27 receiving a nut 28, carried in a socket 29 in the bottom of the foot forward of the arch of the foot. The cable is passed through a bore 30 in the leg and a hole 31 in the flange 16.

The ankle joint is substantially identical to the knee joint but separate numerals will be given the various parts for clarity. The ankle joint is composed of an eyebolt 32, carrying a socket 33, a ball 34, and a shaft 35 is passed through the central hole in the ball 34. This shaft 35 is secured in place in the foot C by set screws or bolts 36 passed up through the foot and into the shaft ends as shown in Figure 5. This assembly is then set in a solid one piece rubber bushing R. The rubber bushing may be square in cross section as shown in Figure 5, or may be round if desired, the essential feature being only that it take up and bush excessive thrust from end motion as well as side motion and that it permit ankle movement which may be thrust, twist or rocking motion. A nut 37 is then screwed onto the threaded end of the eyebolt 32 to hold it and the entire assembly in position.

The foot C will be provided with such rubber bumpers P as are found necessary the size and shape of these being made to the individual requirements.

Adjustments may be made in the nut 37 on the 75

eyebolt to provide for the desired tension in the foot ankle joint relationship and other adjust-
ments may be made in the knee joint to adjust
for twist, throw, and other unusual individual
motions inherent to the individual using the leg.
For instance in some cases the set screw 17 will
be left loose until the knee assumes its relative
position to meet the requirements of the individual
before the set screw is locked in position.

10 Having thus described my invention I claim:

1. An artificial leg comprising a universally
rotatable ball and socket joint in the ankle and
a universally rotatable ball and socket joint in
the knee, and resilient means associated with the
respective ball and socket joints for returning the
adjoining limbs to normal position following dis-
placement thereof.

20 2. An artificial leg comprising a universally
rotatable ball and socket ankle joint having a
transverse shaft passed through the center of
the ball of the joint with its opposite ends an-
chored in the foot portion of the leg, said resi-
25 lient material being anchored in said leg and
in said foot against displacement but not elastic
deformation in a plane substantially normal to
the longitudinal axis of the leg; resilient ma-
terial disposed on all sides of said ball and socket
30 joint as a cushion between said foot portion and
the lower leg portion of said leg; and a shank
extending from the socket member of said joint
up into the lower leg portion of said leg, thereby
attaching the said foot portion to said lower leg
portion and permitting partial rotary as well as
the usual rocking motion for said foot.

35 3. An artificial leg comprising a foot; a lower
leg portion, said foot being recessed to receive the
lower end of the lower leg portion as the ankle;
a universally rotatable ball and socket joint hav-
ing the ball attached to the foot and the socket
40 attached to the said lower leg portion; and resi-
lient means surrounding the ball and socket
joint, and anchored in said lower leg and in said
foot against displacement but not elastic defor-
mation in a plane substantially normal to the
longitudinal axis of the leg.

45 4. In an artificial leg having a foot member
and an upper leg member articulatively attached
to a lower leg member at respectively opposite
ends thereof, a universally rotatable ball and
50 socket joint forming articulative connection be-
tween the foot member and the lower leg mem-
ber; a universally rotatable ball and socket joint
forming the articulative connection between the
upper leg member and the lower leg member;
55 and resilient means anchored in said lower leg
and in said foot against displacement but not
elastic deformation in a plane substantially nor-
mal to the longitudinal axis of said leg.

5. The combination recited in claim 4, wherein
the ball members of the said joints are secured
60 to the foot member and the upper leg member,
respectively, by means of respective shafts which
pass through the centers of said ball members
and provide transverse rotative axes therefor.

65 6. The combination recited in claim 5, wherein
the socket members of the said joints are re-
spectively secured to the lower leg member by
means of respective shanks extending rigidly
from said socket members.

70 7. The combination recited in claim 6, wherein
the said shank members have threaded anchor-
ages with respect to the lower leg member so the
respective joints are adjustable to satisfy indi-
vidual requirements.

8. The combination recited in claim 7, wherein

the said joint between the foot member and the lower leg member is surrounded by resilient material which provides a cushion between said foot member and said lower leg member.

9. In an artificial leg having a foot member articulatively attached to a lower leg member, a ball and socket joint providing the articulative connection, the ball and socket members of said joint being interfitted for free universal rotative movement; means anchoring the ball member of said joint to said foot member, including a shaft passing through the center of said ball member and providing a transverse rotative axis therefor; means securing the socket member of said joint to said lower leg member, including a shank extending rigidly from said socket member and passing upwardly into a hollow portion of said lower leg member through a bore provided in the latter, and a head threaded on the upper end of said shank, said head bearing downwardly against said lower leg member and being movable upwardly within said hollow; and resilient means between said lower leg member and said foot member, said resilient means including a block of resilient material within which said ball and socket joint is embedded.

10. In an artificial leg having a foot member articulatively attached to a lower leg member, a universally rotatable ball and socket joint providing the articulative connection, and having the ball member thereof secured to the foot member of the leg by means of a shaft passing through the center of said ball member to provide a transverse rotative axis therefor; and resilient means anchored in said low leg and in said foot against displacement but not elastic deformation in a plane substantially normal to the longitudinal axis of said leg.

11. The combination recited in claim 10, wherein the socket member of the joint is secured to the lower leg member of the leg by means of

a shank extending rigidly from said socket member.

12. The combination recited in claim 11, wherein the shank of the socket member of the joint extends upwardly into a hollow portion of the lower leg member of the leg through a bore provided in said lower leg member for the purpose; resilient means is provided between the foot member and the lower leg member on all sides of said ball and socket joint; and the upper end of said shank is provided with a head bearing downwardly against the lower leg member and movable upwardly within said hollow, whereby cushioned relative movement is provided for between the foot member and the lower leg member of said leg.

13. The combination recited in claim 12, wherein the head of the shank is threaded on the end of the shank, so that the resilient means may be adjustably compressed in accordance with individual requirements.

RODERICK W. MCKENDRICK.
